DESIGN FOR A COMBINED HELMET AND CAPE

Natalie Renke, New York, N. Y.

Application December 29, 1942, Serial No. 109,158

Term of patent 3½ years

To all whom it may concern:

Be it known that I, Natalie Renke, a citizen of the United States, residing at New York, in the county of New York and State of New York, have invented a new, original, and ornamental Design for a Combined Helmet and Cape, of which the following is a specification, reference being had to the accompanying drawing, forming part thereof.

bined helmet and cape illustrating my new design.

Figure 2 is a side elevation thereof.

I claim:

The ornamental design for a combined helmet and cape, substantially as shown.

NATALIE RENKE.
